United States Patent Office

JONATHAN CRABTREE, OF PHILADELPHIA, PENNSYLVANIA, ASSIGNEE
TO HORNER BROTHERS, OF SAME PLACE.

Design No. 4,683, dated February 28, 1871.

DESIGN FOR A CARPET-PATTERN.

The Schedule referred to in these Letters Patent and making part of the same.

I, JONATHAN CRABTREE, of the city of Philadelphia, county of Philadelphia, State of Pennsylvania, have invented and produced a new and original Design for Carpets, of which the following is a specification.

The nature of my design is fully represented in the accompanying photographic illustrations, to which reference is made.

Claim.

I claim as my invention—
The design for a carpet, as shown.

JONATHAN CRABTREE.
